UNITED STATES PATENT OFFICE

CHARLES A. JOHNSON, OF DULUTH, MINNESOTA

DESIGN FOR A SECTIONAL LAWN STEP

Application filed February 12, 1931. Serial No. 38,628. Term of patent 14 years.

To all whom it may concern:

Be it known that I, CHARLES A. JOHNSON, a citizen of the United States, in the county of St. Louis and State of Minnesota, residing at 4321 W. 3rd St., Duluth, have invented a new and original ornamental Design for a Sectional Lawn Step.

Fig. 1 is a front elevation of the sectional lawn step, showing my new design.

Fig. 2 is a perspective view thereof.

I claim:—

The ornamental design for a sectional lawn step, as shown.

CHARLES A. JOHNSON.
